FIG. 6

UNITED STATES PATENT OFFICE

THOMAS R. SHAW, OF MINNEAPOLIS, MINNESOTA

COMPUTING DEVICE

Application filed March 7, 1930. Serial No. 433,916.

This invention relates to mechanical computing devices of the type including movable items of information adapted to be made visible at selected locations upon the devices, and usually including stationary indices in connection with which the items of information are read.

The object of the invention is to provide a device of the present class in which will be incorporated various novel and specific features and characteristics of construction designed to render the present device an improvement generally over devices of similar nature heretofore known.

With the above object in view, as well as others which will appear as the specification proceeds, the invention comprises the construction, arrangement and combination of parts as now to be fully described and as hereinafter to be specifically claimed, it being understood that the disclosure herein is merely illustrative and intended in no sense as limiting, changes in details of construction and arrangement of parts being permissible so long as within the scope of the claims which follow.

In the accompanying drawings forming a part of this specification,

Fig. 1 is a plan view of a computing device in which the features of the invention are incorporated;

Fig. 2 is a transverse sectional view taken on line 2—2 in Fig. 1;

Fig. 3 is a transverse sectional view, taken on line 3—3 in Fig. 1;

Fig. 4 is a longitudinal sectional view, taken as on line 4—4 in Fig. 2;

Fig. 5 is an end elevational view of the device with the cover removed, detailing the manner of association of the end plates with the base of the casing;

Fig. 6 is a plan view of a modified type of stationary index for the device; and

Fig. 7 is a transverse sectional view, corresponding generally with the disclosure of Fig. 2, but showing a device including the modified type of stationary index of Fig. 6.

With respect to the drawings and the numerals of reference thereon, 10 denotes, generally, the computing device, which consists

of a base 11 having upturned front and rear flanges, designated 12 and 13, end walls 14 each removably associated with the upturned flanges 12 and 13 at the opposite ends of the base 11, and a cover 15 detachably connected to the upturned flanges 12 and 13 and fitted down against the upper edges of the removable end walls 14. As more clearly shown in Figs. 4 and 5, the opposite ends of each of the upturned flanges 12 and 13 are shaped to provide oppositely disposed guideways 16 at the opposite ends of the base 11 in which the side edges of the end walls 14 are snugly fitted to be slidable. The bottom edges of the end walls are desirably fitted into beads at the ends of the base 11. Each end wall is desirably of about the shape as best disclosed in Fig. 5. That is to say, each end wall has a straight lower edge 17, straight side edges 18 extending perpendicular to said bottom edge and slidable in the guideways 16, and a generally curvilinear upper edge 19, which slants somewhat downwardly from rear to front of the casing. The rear upturned flange 13 is preferably of greater width than the front upturned flange 12 to terminate at slightly higher elevation. The cover 15 is desirably of about the shape as best disclosed in Figs. 1, 2 and 3. That is to say, the cover is of curvilinear conformation to fit against the upper edges of the end walls 14, said cover including beads 20 at its opposite ends in which the upper edges 19 of the end walls 14 lie, a rear edge portion 21 overlapping the upper edge of the rear upturned flange 13 and having lugs 22 engaging slots 23 in said rear upturned flange, and a front edge portion 24 overlapping the upper edge of the front upturned flange 12 and having lugs 25 engaging slots 26 in said front upturned flange.

The end walls 14 support shafts, denoted 27, 28 and 29 respectively, the opposite ends of each shaft including reduced portions removably fitted into openings 30 in said end walls. The shafts 27 and 29 support rollers, designated 31 and 32, which are freely rotatable upon said shafts. The shaft 28, which is between the shafts 27 and 29, supports a drive gear 33 within the casing and

adjacent one of the end walls 14, the end wall at the right in Figs. 1 and 4, and said shaft 28 suitably supports a manipulating piece 34 at the outer side of said end wall 14. The shafts 27 and 29 fixedly carry pinions, designated 35 and 36, with which the gear 33 meshes.

Each roller 31 and 32 includes end cups 37 having bearings 38 for the shafts 27 and 29, and collars 39 fixed to shafts 27 and 29 and engaging the outer faces of said end cups hold the rollers 31 and 32 against longitudinal movement. A collar 39 upon each shaft 27 and 29, the collars at the left in Fig. 4, suitably supports a spring clip 40, said spring clips encircling said collars and having their outer ends 41 lying in engagement with the inner peripheries of the rollers 31 and 32 in such manner that when the manipulating piece 34 is rotated in one direction one of the spring clips 40 will drive its corresponding roller by reason of the engagement of its outer end 41 with the inner periphery of said roller, while the other spring clip will freely slide over its corresponding roller, and when said manipulating piece is rotated in opposite direction said other roller will be positively advanced while the corresponding spring clip will freely slide over the first mentioned roller.

Numerical 42 represents a strip of suitable material which contains items of information and has one of its ends suitably and removably secured to the roller 31 and its other end suitably and removably secured to the roller 32. As shown in Figs. 2 and 3, the strip 42 is wound in opposite directions upon the rollers 31 and 32, so that as the strip is unwound from one roller it is wound upon the other roller.

Numerical 43 indicates a backing member, disposed above the shaft 28 at about the elevation of the upper portions of the rollers 31 and 32, having its opposite ends 44 removably fitted in slots 45 in the end walls 14. An intermediate portion of the strip 42 passes over the backing member, as will be more clear from Figs. 2, 3 and 5.

The cover 15 has a sight aperture 46, and a stationary index 47 is removably secured to the inner face of said cover beneath said sight aperture, as by metal strips 48 which receive small screws 49 passing through the cover. (See Fig. 3.) Thus, the stationary index is removably supported beneath the sight aperture, and can be easily replaced by a different stationary index when this is desirable.

As shown in Figs. 1 and 2, the stationary index has parallel sight openings denoted 50 and 51, the opening 50 being directly above the backing member 43, and the opening 51 being directly above the roller 32. By reference to these figures, it will be apparent that the roller 32 presents one surface of the strip

42 to the sight opening 51, while the other surface of said strip is presented at the location of the backing member 43 to the sight opening 50.

Rotation of the manipulating piece 34 will, through the gear 33 and the pinions 35 and 36, cause the rollers 31 and 32 to turn in opposite directions, to thus wind the strip 42 upon one roller while unwinding said strip from the other roller. As a consequence, the rollers will, evidently, have variable rotation relatively to each other. It is for this reason that the shafts 27 and 29 having the gears 35 and 36 are not directly connected to the rollers 31 and 32, but are arranged to drive said rollers through the spring clips 40. As shown in Fig. 3, the spring clip at the left is set to drive its roller when the manipulating piece 34 is turned to rotate the shaft 27 in clockwise direction, and to slide over said roller when said shaft is driven in anti-clockwise direction. The spring clip at the right in said Fig. 3 drives its corresponding roller when the shaft 29 is rotated in anti-clockwise direction and slides over said roller when said shaft is rotated in clockwise direction. That is to say, when the manipulating piece 34 is rotated to advance the strip, one of the rollers is positively wound, while the other roller is free to idle due to the winding of the strip 42 upon the roller which is positively wound.

As shown in Fig. 1, the stationary index 47 contains a "Coal value table", and the strip 42 contains information to be read through the slots 50 and 51 in connection with said "Coal value table". In Fig. 6 I have shown a stationary index 52 having aligning sight openings 53. The present stationary index has thereon a "Grain table" and the strip utilized with such an index would contain items of information in connection with which the "Grain table" is to function.

In Fig. 7 I have shown a cross sectional view of a computing device, approximately similar to the device already described, but having thereon a stationary index 52 with a single row of sight openings 53. In the present instance, the strip need not pass from the lower edges of the rollers 31 and 32 upwardly over the backing member 43, because but a single side of the strip is to be displayed. As shown in Fig. 7, the strip 42 passes directly from the tops of the rollers 31 and 32 over the backing member.

In manufacturing the present computing device, the shafts 27, 28 and 29, having thereon the rollers and gears as described, and the backing member 43, will be associated with the end walls 14 while removed from the base 11. The unit consisting of said end walls, shafts, rollers, gears, and backing member will then be associated with the base 11 by sliding the edges 18 of said end walls 14 into the guideways 16 of the upturned flanges 13.

12 and 13 upon said base, in the manner as will be clear from Fig. 5. Thereafter, the cover 15 will be fitted down upon the upper edges of said end walls, and the lugs upon 5 the front and rear edge portions of said cover will be made to engage the slots in the front and rear upturned flanges. Obviously, the casing of the computing device will thus be securely closed, but can be easily taken apart 10 by a reversal of the operations as just described.

An important feature of the present invention resides in the fact that the computing device can be made standard to be utilized 15 in connection with movable items of information upon the strip 42 of any character, the only changes in the device to adapt it for a different use being replacement of an unsuitable strip 42 by a suitable strip, and the 20 replacement of an unsuitable stationary index 47 by a suitable one. The stationary indices 47 are very readily removable and replaceable simply by withdrawal and proper replacement of the screw 49. The strips 42 25 can be just as easily removed and replaced.

I claim as my invention:

1. In a device of the character described, a casing including a base, upstanding front and rear flanges upon said base and having 30 guideways at the opposite end portions thereof, removable end walls for said casing substantially vertically slidable in said guideways, and a web supporting roller mounted in said end walls to connect the same, said 35 removable end walls and said web supporting roller together constituting a separable unit of the device.

2. In a device of the character described, a casing including a base, upstanding front and 40 rear flanges upon said base and having substantially vertical guideways at the opposite end portions thereof, removable end walls for said casing having their end marginal portions slidably mounted in said guideways 45 and their lower edges engaging said base, and a web supporting roller having its opposite end portions removably mounted in said end walls, said web supporting roller and said end walls being associative with said guideways 50 as a separable unit.

3. In a device of the character described, a casing including a base, upstanding front and rear flanges upon said base and having guideways at the opposite end portions thereof, removable end walls for said casing substantially vertically slidable in said guideways, spaced apart web supporting rollers mounted in said end walls, and a web backing member mounted in said end walls, said end 60 walls, supporting rollers, and backing member together constituting a separable unit of the device.

4. In a device of the character described, a casing including a base, upstanding front 65 and rear flanges upon said base and having

substantially vertical guideways at the opposite end portions thereof, removable end walls for said casing having their end marginal portions slidably mounted in said guideways and their lower edges engaging 70 said base, spaced apart web supporting rollers having their opposite end portions removably mounted in said end walls, and a web backing member having its opposite end portions removably mounted in said end walls, said 75 end walls, supporting rollers, and backing member together constituting a separable unit of the device.

5. In a device of the character described, a casing including a base, upstanding front and rear flanges upon said base and having guideways at the opposite end portions thereof, removable end walls for said casing slidable in said guideways, a web supporting 80 roller mounted in said end walls, and a cover removably fitted upon said end walls, said 85 cover including front and rear portions extending along the upper portions of the ends of said end walls and meeting with said front and rear flanges upon said base, said base and upstanding front and rear flanges upon said 90 base and having said guideways constituting one unit of said device, said removable end walls and supporting roller constituting a second unit of said device, and said cover constituting a third unit of said device, said second unit as such being associative with said first mentioned unit, and said third unit being associative with said first mentioned unit to, 95 together therewith, house said second unit. 100

6. In a device of the character described, a casing including a base, upstanding front and rear flanges upon said base and having guideways at the opposite end portions thereof, removable end walls for said casing slidable in said guideways, a web supporting roller mounted in said end walls, and a cover removably fitted upon said end walls, said 105 cover including front and rear portions overlapping said front and rear flanges, respectively, and said portions and flanges including complementary means detachably securing said cover to said base, said base and upstanding front and rear flanges upon said base and having said guideways constituting one unit 110 of said device, said removable end walls and supporting roller constituting a second unit of said device, and said cover constituting a third unit of said device, said second unit as such being associative with said first mentioned unit, and said third unit being associative with said first mentioned unit to cover 115 said second unit. 120

In witness whereof, I have hereunto set my hand this 5th day of March, 1930.

THOMAS R. SHAW.
